UNITED STATES PATENT OFFICE

WALTER J. F. LIDDELL, OF CHARLOTTE, NORTH CAROLINA.

MACHINE FOR MOLDING PULLEYS.

SPECIFICATION forming part of Letters Patent No. 333,765, dated January 5, 1886.

Application filed April 20, 1885. Serial No. 162,830. (No model.)

To all whom it may concern:

Be it known that I, WALTER J. F. LIDDELL, of Charlotte, county of Mecklenburg, and State of North Carolina, have invented a new and 5 useful Improvement in Apparatus for Mold- ing Pulleys, of which the following is a full, clear, and exact description, reference being had to the accompanying drawings, making part of this specification.

10 My invention relates to the means for forming molds for pulleys or band-wheels; and it consists in the employment, in combination with the two parts or halves of the flask or mold, of a templet or bed-plate and a half- 15 pattern of the pulley to be formed, adapted by their construction to be connected to each other and to the two parts of the mold, in uniform relation to the latter, in such manner that when the half-molds are formed and the 20 two parts thereof joined, as hereinafter explained, they will exactly coincide and form the complete mold, as hereinafter described; whereby, also, the bed-plate is made to constitute a templet or gage for indicating the 25 position of the pins and holes in the two parts of the flask, as hereinafter explained.

In the accompanying drawings, Figure 1 is a plan view of the cope or upper half of the flask; Fig. 2, a similar view of the drag or 30 nowel. Fig. 3 represents a section through the cope, taken on line ww , Fig. 1; and Fig. 4, a similar section on line xx of Fig. 2. Figs. 5 and 6 represent vertical sections through the bed-plate or templet and half-pulley pattern, and Fig. 7 a plan view of the half-pulley pattern. Figs. 8 and 9 represent sections 35 through the two parts of the mold, taken on the lines yy and zz , respectively, of Figs. 1 and 2, and of the bed-plate and half-pattern, 40 and Fig. 10 is a similar section through the mold, with the bed-plate and pattern removed and the two halves joined; and Fig. 11 is a plan view of the bed-plate adapted for use for different-sized pulleys and flasks or 45 molds, and as a templet for marking or gag- ing the position of the holes and pins in the parts of the latter.

A represents the cope or upper part of the flask, made preferably hexagonal in form, 50 conforming to the number of arms or spokes of the pulley, and provided with suitable in-

tersecting webs, a , or cross-bars, connecting its sides or shell and adapted to permit the ready filling of the half-flask and the tamping of the sand therein from above, and also to 55 assist in the retention of the sand, the web having suitable openings, a' , to permit the insertion of the half-pattern therein.

B represents the lower part or half of the flask, similarly formed and open on its upper 60 face, to permit it to be inverted over the bed-plate and half-pattern, as shown in Fig. 10. These two parts are provided on their faces which are to be joined with outwardly-projecting horizontal flanges a^2 and b , extending 65 around them, and provided each at regular intervals with a series of pins, a^3 and b' , and holes a^4 and b^4 , arranged to alternate, as shown, so that when the cope or upper half, A, is placed upon the drag or lower half, B, 70. the pins of one part will enter the holes of the other part, as shown in Fig. 10. The two parts A and B of the flask are provided each with the usual handles, C.

D is a bed-plate provided on its lower face 75 with an annular flange, D', or with suitable feet upon which it may rest, raised sufficiently above the table or support on which it is to rest to permit the pins a^3 or b' to project through it, and further provided with a series 80 of perforations, d , arranged in a circle and equidistant from each other, and through which said pins may pass, as shown in Figs. 8 and 9. The plate D is provided with a central hub or spur, d' , adapted to enter a central hole in the half pattern for centering the latter, and upon opposite sides of said central hub with holes d^2 , to receive pins on opposite 85 arms of the half-pattern, for holding the latter in place.

E is the pattern, made in the form of a half-pulley, and provided preferably with six arms, (any suitable number or a continuous disk may be employed,) as giving the necessary support to the rim or peripheral 95 flange E', uniting their outer ends with a central perforation, e , to receive the hub or spur d' , and with pins $e' e'$, entering the holes d^2 of the plate D, for centering and holding the half-pattern in place on said plate D, as explained.

With the parts of the flask, the plate D,

and the half-pattern, formed as described, the half-pattern is secured in place on the plate D, and the drag or the cope, the former inverted, is placed over the plate and half-pattern, with the pins a^3 or b^4 entering alternate holes of series d , and is then filled and properly tamped from above, after which it is removed, the half-pattern drawn and placed upon the plate D, and another half-flask is put in place on the latter and prepared in a similar manner. Any desired number of half-flasks may thus be prepared and afterward put together, in the manner indicated in the sectional view, Fig. 11, and being exact duplicates, each half of the other corresponding half-flask, they unite to form the complete mold, as shown.

In Fig. 11 I have shown the bed-plate D provided with several series of perforations, whereby it is adapted for use with flasks and in the molding of pulleys of different sizes, and also as a templet for marking or gaging the position of the alternate pins and perforations of the two parts of the flask, and also of the pins on the half-pattern, adapting the plate to the marking of larger flasks for the pins and holes and to receive such flasks for forming larger or smaller pulleys, as desired. Other perforations, d^2 , may be employed, if desired, for holding the pins on the pattern, varying in distance from the central spur or pin, d^1 , according to the diameter or length of arms of such pattern. The plate D, thus constructed, forms a convenient device for marking the parts of the flask for the pins, and holes for uniting them to each other or to

the bed-plate, which may be done by placing the said templet upon the bottom of the half-flask and boring through the perforations of the templet, or by marking through the same, and thus designating the points at which the pins or holes in the flask are to occur, and by having the pins and holes to alternate in the two parts of the flask the latter are adapted to come together always in uniform relation one to the other.

Having now described my invention, I claim as new—

1. In an apparatus for molding pulleys, the bed-plate or templet provided with the series of holes arranged equidistant from each other in circles, and with means for holding the half-pulley pattern in place thereon, substantially as and for the purpose described.

2. In an apparatus for molding pulleys, the combination of the bed-plate having the series of holes arranged in concentric circles for the reception of the parts of flasks of different diameters, the two parts of the flask and the half-pulley pattern, each provided with pins engaging the bed-plate, and the latter adapted to serve as a templet for locating said pins on the parts of flasks, and half-pulley patterns of different diameters, all substantially as described.

In testimony whereof I have hereunto set my hand this 18th day of April, A. D. 1885.

W. J. F. LIDDELL.
